(57) **CLAIM**

The ornamental design for a combined game board and playing cards, as shown and described.

DESCRIPTION

FIG. 1 is a top view of a game board for a combined game board and playing cards showing my new design;
FIG. 2 is a bottom view thereof;
FIG. 3 is a right side elevational view thereof, the left side elevational view being identical;
FIG. 4 is a front elevational view thereof, the rear elevational view being identical;
FIG. 5 is a top view of a first playing card for the combined game board and playing cards;
FIG. 6 is a right side elevational view of the first playing card, the left side elevational view being identical;
FIG. 7 is a front elevational view of the first playing card, the rear elevational view being identical;
FIG. 8 is a bottom view of the first playing card;
FIG. 9 is a top view of a second playing card for the combined game board and playing cards;
FIG. 10 is a right side elevational view of the second playing card, the left side elevational view being identical;
FIG. 11 is a front elevational view of the second playing card, the rear elevational view being identical;
FIG. 12 is a bottom view of the second playing card;
FIG. 13 is a top view of a third playing card for the combined game board and playing cards;
FIG. 14 is a right side elevational view of the third playing card, the left side elevational view being identical;
FIG. 15 is a front elevational view of the third playing card, the rear elevational view being identical; and,
FIG. 16 is a bottom view of the third playing card.
